Patented Dec. 8, 1970

219,392

ROTATABLE SANDER

Robert J. Doherty, 231 N. Washington St.,
Hinsdale, Ill. 60521

Filed Aug. 28, 1968, Ser. No. 13,304

Term of patent 14 years

Int. Cl. D8—02

U.S. Cl. D37—1

FIG.1

FIG.3

FIG.2

FIG.4

FIG. 1 is a top perspective view of a rotatable sander showing my new design;

FIG. 2 is a bottom perspective view thereof;

FIG. 3 is a side elevational view thereof;

FIG. 4 is a top perspective view of a rotatable sander showing another form of my new design wherein the placement of the scooplike elements is modified from the form shown in FIGS. 1-3.

The dominant features of my design reside in the portions shown in full lines.

I claim:

The ornamental design for a rotatable sander, substantially as shown and described.
